UNITED STATES PATENT OFFICE.

CHARLES J. HAUCK, JR., OF BROOKLYN, NEW YORK.

METAL BOX.

SPECIFICATION forming part of Letters Patent No. 448,034, dated March 10, 1891.

Application filed January 3, 1891. Serial No. 376,636. (No model.)

To all whom it may concern:

Be it known that I, CHARLES J. HAUCK, Jr., a citizen of the United States, residing at Brooklyn, E. D., in the county of Kings and 5 State of New York, have invented new and useful Improvements in Metal Boxes, of which the following is a specification.

This invention relates to a sheet-metal box which is intended particularly for matches, 10 cigarettes, or cigars.

The peculiar and novel construction of my box is pointed out in the following specification and claims, and illustrated in the accompanying drawings, in which—

15 Figure 1 is a side elevation when the box is closed. Fig. 2 is a similar view when the box is open. Fig. 3 is a vertical section in the plane y y , Fig. 4. Fig. 4 is a horizontal section in the plane x x , Fig. 1.

20 In the drawings, the letter A designates the body of my box, which is by preference made oval in cross-section and provided at the top of each side with a finger-opening a , so that when the box is open, as shown in Fig. 2, the 25 matches, cigarettes, or other articles contained therein can be conveniently reached and withdrawn. From the opposite sides of the body A extend the pivots b b , (best seen in Fig. 4,) and on these pivots are mounted 30 the lower ends of the semi-lid B and the lower ends of the overhanging flanged d , formed on or secured to the semi-lid C, so that said lids can be brought into the position shown in Figs. 1 and 3 for the purpose of 35 closing the box, or that they can be moved to the position shown in Fig. 2 for the purpose of getting access to the contents of the box. The lower edge c of each semi-lid is made to run in an oblique direction from the 40 pivots b upward, so that the same can be swung from the position shown in Fig. 1 to the position shown in Fig. 2. By the oblique arrangement of the edges c they are caused

to diverge from the pivots b , and such divergent edges extend or run round the sides of 45 the box-body A in such manner that when the semi-lids B and C are opened their lower edges bear against opposite side portions of the box-body, and therefore the box-body constitutes a support for each lid in its open 50 position. The flange d on the semi-lid C overlaps the edge of the semi-lid B, so that when the two semi-lids are closed the contents of the box are protected against dust or other impurities, and at the same time this flange 55 is so formed that it produces sufficient friction against the semi-lid B to retain the lids in their closing position.

What I claim as new, and desire to secure by Letters Patent, is—

60 1. The combination, with the box-body A, having the two opposite pivots b b , of the two semi-lids B C, mounted on the pivots to swing in opposite directions and having their lower edges c extending round the box-body and 65 coming to rest against the opposite sides of such box-body when the lids are opened, substantially as described.

2. The combination, with the box-body A, having the two opposite pivots b b , of the 70 semi-lids B C, one of which is mounted at its lower edge on the pivots and the other one provided with the overhanging flange b , having its lower ends mounted on the pivots, 75 said semi-lids having divergent lower edges c , extending round the box-body and coming to rest against opposite sides of such body when the lids are opened, substantially as described.

In testimony whereof I have hereunto set 80 my hand in the presence of two subscribing witnesses.

CHARLES J. HAUCK, JR.
